MANUAL SWITCHBOARD

Erik Isidor Engquist, Stockholm, Sweden, assignor to Telefonaktiebolaget L. M. Ericsson, Stockholm, Sweden, a company of Sweden

Application November 4, 1941, Serial No. 417,842
In Sweden July 20, 1940

9 Claims. (Cl. 179—55)

The invention relates to manual switchboards of the cordless class, that is to say, switchboards in which both the line wires for every subscriber may be connected to an operator's telephone set, cord circuit and the like by means of a plug which alternatively may be inserted into a number of jacks arranged for every subscriber. Hitherto known switchboards of this class have been of a complicated construction and have not made it possible easily to enlarge the switchboard when necessary. The object of the invention is to eliminate these disadvantages and the invention mainly consists therein that the line wires for every subscriber are connected to two bare conductor wires arranged at the jacks belonging to the subscriber in such a manner that a spring connection between the wire and the plug is obtained.

The invention will now be described more in detail with reference to the drawings attached, said drawings showing an embodiment of the invention. Fig. 1 is an elevation of one of the units of which the switchboard has been built up and shows a front view of the unit. Fig. 2 is a bottom plan view of the unit. Figs. 3 and 4 are sections taken on the line A—A in Fig. 1 showing, respectively, the plug withdrawn and inserted. Fig. 5 is a diagram.

1 indicates a plate of Bakelite or the like being enlarged along one edge and provided with a recess 2 for each jack. A metal wire 3, 4 preferably of phosphorbronze is fastened to each side of the plate. Said wires rest against the surface of the plate and are fastened to the same by means of clamps 8, which are put through holes in the plate and are bent up on the other side of the plate. For every jack, two contact springs 5 and 6 are provided and riveted on opposite sides of the plate 1. Fig. 3 shows the said wires and springs in the rest position, that is to say, the position which they occupy when the plug is not inserted and Fig. 4 shows the position after the insertion into the jack of the plug P, the latter being of standard construction, having two cylindrical, conductive parts, divided by an insulating part. As shown in Fig. 4 the wires 3 and 4 are bent out between their fixing points by the insertion of the plug, a spring contact thus being established between wire and plug. Also when the plug is inserted into the jack the wires 3 and 4 are electrically connected to the contact springs 6 and 5, respectively. The plate 1 is supported by a plate 7, which may be fastened in a rack. Said plate also supports a call indicator K for the line. By mounting a number of the above de-

scribed units in the rack, and then connecting the corresponding contact springs in the units with each other, mainly by using bare wire connections, a switchboard of the capacity desired is obtained. 5 With an increase of the number of subscribers the switchboard may be enlarged in a simple way by inserting one or several new units into the rack. Fig. 5 is a switching diagram for a switchboard made of three units. A, B, C indicate the subscribers' lines each of which is connected to the bare wires 3, 4. Each subscriber's line is provided with four jacks J₀—J₃. 5, 6 indicate the contact springs in each jack, whereby the corresponding springs in the jacks of the different units, except the springs in the jacks J₀, are connected to each other, so as to form firstly two cord circuits S₁ and S₂ and secondly an operator's line T. The contact springs in the upper jack J₀ in every unit are connected to a call indicator K. Each cord circuit S₁ and S₂ is connected to the supervisory indicator U. Normally every subscriber's plug is inserted into the jack J₀. When a call is indicated by the call indicator K, the plug is shifted to J₁ in order to be connected 10 with the operator's telephone set M, R, whereupon the plug is inserted into one of the jacks J₂, J₃ depending upon which one of the cord circuits is idle.

The invention is of course not limited to the embodiment above described but may be modified in several ways within the limits of the invention idea.

I claim:

1. An arrangement for manual switchboards of the cordless class by which both the line wires for each subscriber may be connected to cord circuits, operator's telephone set, and the like, by means of a plug comprising a plurality of jacks for selective reception of said plug, said jacks including two bare wires connected with the line wires of each subscriber and adapted to make spring contact with the inserted plug.
2. An arrangement as claimed in claim 1, characterized by the provision of a body of insulating material supporting a group of jacks related to an individual subscriber and constituting a removable unit.
3. An arrangement as claimed in claim 1, characterized by the provision of a call indicator, a body of insulating material supporting the several jacks relating to an individual subscriber and forming a removable unit connected to said call indicator.
4. An arrangement as claimed in claim 1, characterized by the provision of a supporting

body for said jacks having recesses therein for the reception of a plug, said bare wires extending across said recesses for engagement by the plug.

5. An arrangement as claimed in claim 1, characterized by the provision of an insulating support for the jacks having recesses therein for the reception of a plug, the bare wires being arranged at opposite sides of the recess for contact with the inserted plug.

6. An arrangement for manual switchboards of the cordless type by which both the line wires for each subscriber may be connected to cord circuits, operator's telephone set and the like, by means of a plug comprising a plate-like support having recesses therein for receiving the plug, bare wires fastened to said support and extending across the several recesses for making spring contact with the inserted plug.

7. An arrangement as claimed in claim 6,

characterized in that the wires are arranged on the opposite sides of the plate-like support.

8. An arrangement as claimed in claim 6, characterized by the provision of a spring contact associated with each bare wire and arranged at the side of the recess opposite thereto.

9. An arrangement for manual switchboards of the cordless class by which both the line wires for each subscriber may be connected to cord circuits, operator's telephone set and the like by means of a plug comprising a plurality of jacks for selective reception of said plugs, said jacks including two bare wires connected with the line wires of each subscriber for making spring contact with the inserted plug, at least one of said wires being so arranged as to be bent outwardly incident to the insertion of said plug.

ERIK ISIDOR ENGQUIST.
